UNITED STATES PATENT OFFICE.

SOZABURO TODA, OF ERIE, PENNSYLVANIA.

COMBINED SIFTER AND MIXER.

Specification of Letters Patent.

Patented Jan. 16, 1917.

1,212,585.

Application filed June 14, 1915. Serial No. 34,003.

To all whom it may concern:

Be it known that I, SOZABURO TODA, a subject of the Emperor of Japan, residing at Erie, in the county of Erie and State of Pennsylvania, have invented certain new and useful Improvements in Combined Sifters and Mixers, of which the following is a specification.

This invention relates to combined sifters and mixers for flour and the like, and has for one of its objects to simplify and improve the construction and increase the efficiency and utility of devices of this character.

Another object of this invention is to provide a simply constructed device which may be employed for simultaneously mixing and sifting materials or for mixing alone without sifting.

With these and other objects in view, the invention consists in certain novel features of construction as hereinafter shown and described and then specifically pointed out in the claims; and in the drawings illustrating the preferred embodiment of the invention. Figure 1 is a sectional elevation transversely of the operating shaft; Fig. 2 is a sectional elevation longitudinally of the operating shaft; Fig. 3 is a plan view with the shell in section on the line 3—3 of Fig. 1; Fig. 4 is a view in section on the line 4—4 of Fig. 1; Fig. 5 is a plan view of the blank from which the agitator member is constructed; Fig. 6 is a detail view of one of the clip devices whereby the agitator members are coupled to the shaft.

Corresponding and like parts are referred to in the following description and indicated in all the views of the drawings by the same reference characters.

The improved device comprises a shell 10 open at both ends and with the upper or receiving end inclined, as indicated at 11. The shell is provided with the usual annular beads 12 to indicate the quantity of material and with a larger annular bead 13 which constitutes an inwardly opening annular channel. Formed in the walls of the shell at opposite sides and just below the larger bead or channel 13 are segmental slots, indicated at 14. Located within the shell 10 is a cup-shaped member 15 having an outwardly directed rim 16 turned over upon

itself to form an annular channel, the turned over portion of the rim engaging in the relatively large bead 13 and supported in position thereby. The cup-shaped member is sprung into the bead 13 and requires no other fastening. Located within the cup-shaped member is a cup-shaped screen indicated at 17 and with an outturned rim 18 engaging within the channel formed by the turned over portion 16 of the cup-shaped member. By this means the screen of the cup-shaped member is firmly secured in position relatively to the shell 10 and effectively prevented from movement in any direction. The cup-shaped member 15 is provided with a plurality of radially directed openings 19 with the "lands" or spaces between the openings slightly greater than the openings, as shown in Fig. 4.

Located within the cage in transverse alignment with the slots 14 is an annular frame 20 having lateral projections 21 extending through the slots 14. By this means the annular frame is supported from vertical movement relative to the shell while at the same time free to be rotated within the shell by the engagement of the projections 21 in the slots. One or both of the projections 21 project beyond the shell 10 a sufficient distance to enable the frame 20 to be oscillated a distance equal to the lengths of the slots. Supported upon the frame 20 is another cup-shaped member 22 which corresponds to and is closely engaged by the first-mentioned cup-shaped member. At its upper edge the cup-shaped member 22 is provided with an outturned rim engaging upon and supported by the frame 20, and is likewise provided with a plurality of radial openings 23 corresponding to the openings 19 and registering therewith when the frame 20 and the cup-shaped member supported thereby is disposed in one position, and cut off by the imperforate portions of the cup-shaped member 15 when in another position, by this means it will be obvious that the material deposited in the shell may be sifted through the openings in the cup-shaped members, when the latter are disposed in registering position, and the flow cut off when the oscillating cup-shaped member is disposed in another position.

The cup-shaped member 22 is provided

with a downwardly directed central projection 35, while the inner cup-shaped member 15 is provided with a similar downwardly directed central projection 36 which engages 5 within the projection 35, the two projections coacting to form a "center" to facilitate the rotation of the outer cup-shaped member relative to the inner cup-shaped member.

Mounted for rotation through the shell 10 just above the sifter portion of the improved device is a shaft 24 having an operating handle 25 at one end externally of the shell. The shaft 24 is threaded for a portion of the distance near one end, preferably the 15 end farthest from the handle 25, as shown in Fig. 2. An agitator device is connected to rotate with the shaft and consists of a plurality of blades 26 having perforated disks 27 at their ends. Each of the blades 20 26 is likewise provided with a plurality of laterally projecting lugs 29 which are adapted to be bent at right angles to the path of the blade, as indicated in Figs. 1 and 2.

The members 26 are curved transversely 25 and likewise curved longitudinally, and terminal disks 27 disposed upon the shaft 24 near its ends. Mounted upon the shaft 24 externally of the disks 27 are washers 30 each having radial lugs 31 adapted to be bent over the superimposed disks between the blades 26, and thus firmly anchoring the connected blades to the shaft. One of the washers is threaded to engage the threaded portion of the shaft 24 and thus effectually 35 coupling the blades to the shaft. By this means the blades are connected for rotation with the shaft, as will be obvious.

Any required number of blades 26 may be employed, but generally three will be used 40 as shown. The longitudinal curvature of the blades will correspond to the curvature of the cup-shaped members and the cup-shaped screen and will rotate in close proximity to the screen, as shown in Figs. 1 and 45 2. By this simple means it will be obvious that an effectual sifting of material will be effected by the rotation of the shaft 24 through the medium of the crank 25, and this material may be either sifted through 50 the screen or held within the receptacle and thoroughly mixed by the action of the agitator blades according to the position of the outer or oscillating cup-shaped member, as before described. By curving the blades 26 55 transversely, they pick up a portion of the material and carry it upwardly and drop it down upon the remaining material and thus materially increase the efficiency of the sifting and mixing action, as will be obvious.

60 The improved device is simple in construction, can be inexpensively manufactured and of any required size and of any required capacity.

A suitable stationary supporting handle

represented at 34 will preferably be attached 65 to the shell, as shown.

Having thus described the invention, what is claimed as new is:—

1. In a device of the class described, a shell having an inwardly opening annular 70 channel, a member of foraminous material, a partition member extending transversely of the shell and having a plurality of openings and rolled at its edges over the edge of the foraminous member, the rolled over 75 edge of the partition member frictionally engaging in the channel, and a cut off member coacting with the partition member.

2. In a device of the class described, a shell having an inwardly opening annular 80 bead and transverse slots, a frame having projections engaging in said slots and thereby mounted for oscillation within said shell, a cup-shaped member supported by said frame and movable therewith, said movable 85 cup-shaped member having a plurality of openings spaced apart, another cup-shaped member having its rim rolled over and frictionally engaging in said annular bead and supported thereby within the shell, said 90 frictionally supported cup-shaped member bearing within the movable cup-shaped member and said frictionally supported cup-shaped member having a plurality of openings registering with the openings of 95 the movable cup-shaped member when in one position and closed by the spaces between said openings when in another position, and an agitator operating within the shell and within the frictionally supported 100 cup-shaped member.

3. In a device of the class described, an inclosing shell having an inwardly opening encircling channel and oppositely disposed slots, a transverse member having its rim 105 rolled over and frictionally supported thereby in said channel and having a plurality of openings, and a cut-off member having projections engaging in said slots and mounted for rotation thereby relative to said trans- 110 verse member and having openings adapted to register with the openings of the same.

4. In a device of the class described, an inclosing shell having an inwardly opening encircling bead, a transverse member having 115 a plurality of openings and with its edge rolled over and engaging in said bead, a screen member bearing upon said transverse member and with its edge received in the rolled over edge of the same and supported thereby, a member rotative relative to said transverse member and having openings adapted to register with the openings of the transverse member, and an agitator within the shell.

5. In a device of the class described, a shell, a cup-shaped member mounted for oscillation within said shell and having a plu- 125

rality of openings spaced apart, and another cup-shaped member rigidly supported within the shell and bearing within the movable cup-shaped member, said rigidly supported 5 cup-shaped member having a plurality of openings registering with the openings of the movable cup-shaped member when in one position and closed by the spaces between said openings when in another position,

tion, said shell adapted to support an agitator therein.

In testimony whereof I affix my signature in presence of two witnesses.
